UNITED STATES PATENT OFFICE.

EDWIN F. WILLIAMS, OF ERIE, PENNSYLVANIA.

GOVERNOR CONTROL OF STEAM-ENGINE VALVES.

1,069,990.

Specification of Letters Patent.

Patented Aug. 12, 1913.

Application filed December 16, 1912. Serial No. 737,126.

To all whom it may concern:

Be it known that I, EDWIN F. WILLIAMS, a citizen of the United States, residing at Erie, in the county of Erie and State of Pennsylvania, have invented certain new and useful Improvements in Governor Control of Steam-Engine Valves, of which the following is a specification.

This invention relates to valve gear for steam engines, and comprises a governor for such valve, where one valve controls the admission and the exhaust.

A serious objection to ordinary shaft governor control of a single valve is that at the shorter cut-offs the exhaust action is advanced to such an extent that compression becomes excessive, unless the cylinder clearance is too large for very good economy in the use of steam. It is desirable for various reasons to use a single valve for both of the functions referred to, and it is also desirable to have small cylinder clearance for steam economy. The ordinary governor and shifting eccentric does not admit of short cylinder clearance with a single valve.

The object of the invention is to provide a construction attended with the advantages referred to. The device provides for the movement of a valve under governor control for retarding the exhaust action at various or all periods of admission. It delays, or causes a later exhaust action than would occur at the same cut-off with an ordinary governor mechanism. The invention provides a variable cut-off governor control, in connection with a delayed exhaust.

In the accompanying drawings—Figure 1 is a side elevation of the governor mechanism. Fig. 2 is a sectional view on the line 2—2 of Fig. 1. Fig. 3 is a side elevation opposite to Fig. 1. Fig. 4 is a side elevation, partly in section, illustrating the valve gear connected to a single piston valve controlling the separate inlet and outlet ports.

In the drawings, A is the eccentric arm or lever pivoted to the fly wheel 6 at R, and pivotally connected to and acted on at the other end by a toggle link C, D, E pivoted to the lever J which carries the weight I, said lever being pivoted on a sleeve F which is fastened to one of the fly wheel spokes by nut P. The driving pin B projects from the eccentric arm A and operates the eccentric rod 7.

N is a fixed eccentric which is attached to the engine frame 8, and O is an eccentric

strap mounted thereon and pivoted to one end of a rocker arm G, projecting from a rock shaft L which is mounted in a bearing on one of the fly wheel spokes and extends across the same to the opposite side of the wheel, where the shaft L carries an arm H at its other end. The shaft L extends through the sleeve F which forms the bearing for the same. The arm H is connected by a link K to the toggle joint D.

The eccentricity of the fixed eccentric N is at approximately a right angle to the eccentric rod, and at each revolution of the main shaft or fly wheel the action of the eccentric N by means of the rock shaft L and its arms G and H causes the toggle to flex at its elbow D, thereby shortening the distance between the points C and E a certain amount, twice for each revolution of the governor. The distance between the ends C and E of the toggle is always shortest when the valve is approximately at half travel either forward or back because, as stated, the eccentric is approximately at a right angle to the line of movement of the eccentric rod. As the exhaust always opens and closes at mid stroke of the valve it will be seen that at the time of exhaust the eccentric arm A is thrown back, in a position it would otherwise occupy with the cut-off at a later point of the piston stroke, thereby causing a dwell or delay in the movement of the valve. In this manner there is obtained a variable cut-off, with a delayed exhaust action throughout the range of the governor.

In Fig. 4, the governor is shown applied to a steam engine having a single valve 9 located directly under the bore of the cylinder and controlling at its opposite ends the inlet ports 10 to the cylinder and the outlet ports 12 to the middle exhaust passage 13. Obviously the valve may be located in any other suitable position. The exhaust ports 12 are spaced from the cylinder heads a sufficient distance to secure a desired amount of compression when closed by the piston running over them. When such a valve is combined with the governor mechanism shown there is secured a constant point of exhaust closure and a constant compression in the cylinder, the steam being admitted and exhausted by a single valve which controls the independent inlet and outlet ports and is operated by the governor. With such a

valve the governor produces a delayed exhaust action without correspondingly delaying the point of cut-off, and the movement is also hastened at the time of steam admission, giving quicker admission and a sharper cut-off than would otherwise occur. This feature of accelerated admission is present, although it is not as important to the desired result as the delayed exhaust.

10 13 What I claim as new is:

1. The combination with a shiftable valve-operating eccentric, and means to shift the same, of a fixed eccentric, and means actuated thereby to vary the shift of the first mentioned eccentric.

15 20 23 2. The combination with a wheel, a shiftable valve-operating eccentric carried thereby and rotating therewith, and means to shift said eccentric, of means including a fixed eccentric to periodically vary the shift of said valve-operating eccentric.

25 28 3. The combination with a wheel, a lever carried thereby and provided with an eccentric connection adapted to operate a valve, and means actuated by the rotation of the wheel to shift the lever, of a fixed eccentric located beside the wheel, and means actuated thereby to periodically vary the position of the lever, during such rotation.

30 33 35 4. The combination with a wheel, a shiftable valve-operating eccentric carried thereby, a weighted lever carried by the wheel and actuated by rotation thereof, and a connection between said lever and eccentric to shift the latter by movement of the former, of means to periodically vary the effective length of said connection and thereby

modify the shift of said eccentric, during the rotation of the wheel.

5. The combination with a wheel, a shiftable valve-operating lever carried by said wheel, a weighted lever carried by the wheel and actuated by rotation thereof to shift the said lever, and a jointed connecting link between the levers, of auxiliary means to periodically flex the link at said joint and thereby vary its effective length, during the rotation of the wheel.

6. The combination with a wheel, a shiftable valve-operating lever carried by said wheel, a weighted lever carried by the wheel, and a jointed connecting link between the levers, of a fixed eccentric beside the wheel, an eccentric strap thereon carried by the wheel, and a connection between said strap and the link, adapted to flex the latter and vary its effective length.

7. The combination of a wheel, a shiftable valve-operating eccentric carried thereby, a weighted lever carried by the wheel, a toggle connecting the eccentric and the lever, a rocker carried by the wheel and connected to the toggle and adapted to flex the latter, and a fixed member located beside the wheel, and an operating connection between said member and the rocker, adapted to periodically actuate the latter during the rotation of the wheel.

In testimony whereof, I do affix my signature in presence of two witnesses.

EDWIN F. WILLIAMS.
